UNITED STATES PATENT OFFICE.

PAUL PASCAL PIERCE, OF CASTILE, NEW YORK.

SOAP-HOLDER.

1,146,275.

Specification of Letters Patent. Patented July 13, 1915.

Application filed November 25, 1913. Serial No. 802,972.

To all whom it may concern:

Be it known that I, PAUL P. PIERCE, a citizen of the United States, residing at Castile, in the county of Wyoming, State of New York, have invented certain new and useful Improvements in Soap-Holders; and I do hereby declare the following to be a full, clear, and exact description of the invention, such as will enable others skilled in the art to which it appertains to make and use the same.

The present invention is directed to improvements in soap holders, and has for its object to so construct a device of this character that the same can be easily and quickly attached to the smooth surface of a bath tub or wash basin.

A further object of the invention is to so construct a soap holder that the same will be disposed horizontally within the tub and in convenient reach of the bather.

With these and other objects in view, this invention resides in the novel features of construction, formation, combination and arrangement of parts to be hereinafter more fully described, claimed and illustrated in the accompanying drawing, in which:—

Figure 1 is a side elevation of the device, showing the same in place upon a bath tub, the tub being shown in section. Fig. 2 is a front view of the device. Fig. 3 is a sectional view on line 3—3 of Fig. 1. Fig. 4 is a top plan view.

Referring to the drawing, the numeral 1 designates the soap dish which may be of design and has depending from its bottom a downwardly and outwardly curved rod 2, the lower end of which terminates in a horizontally disposed elongated plate 3 designed to contact with the side of the tub 4.

A rubber vacuum cup 5 is provided and has connected thereto an arm 6, said arm

having its outer end secured to the bottom of the dish 1 in any suitable manner.

When it is desired to apply the holder the 45 vacuum or suction cup is pressed against the tub or basin so as to expel the air therefrom, and upon releasing the pressure from the cup, the suction created thereby will cause the cup to adhere to the tub or basin. Thus 50 in addition to the rod 2 and plate 3, the latter contacting with the sides of the tub or basin, the soap dish will be effectually supported in convenient reach of the bather.

The upper end of the rod 2 is provided 55 with a flat head 7, which can be readily secured to the bottom of the soap dish 1 by a rivet, or it may be soldered as desired. The outer end of the arm 6 may be secured to the bottom of the dish in a similar manner. 60

What is claimed is:—

In a device of the class described, the combination with a soap dish, of an arm secured to the bottom thereof and extending outwardly beyond the edge of the dish at one 65 side thereof, a suction cup secured to the outer end of said arm constructed and arranged to grip a supporting member, a bracing rod secured to the bottom of the dish in spaced relation to the point of securement of 70 the arm and adjacent the opposite edge of the dish, the said rod extending downwardly and then horizontally parallel to the said arm and a plate carried by the end of the said rod constructed and arranged to engage the support below and in spaced relation to the suction cup.

In testimony whereof, I affix my signature, in the presence of two witnesses.

PAUL PASCAL PIERCE.
